UNITED STATES PATENT OFFICE.

CHARLES S. BAILEY, OF WALTHAM ABBEY, COUNTY OF ESSEX, ENGLAND.

CENTRAL-FIRE CARTRIDGE.

SPECIFICATION forming part of Letters Patent No. 268,601, dated December 5, 1882.

Application filed April 11, 1882. (No model.) Patented in England February 1, 1882, No. 496.

To all whom it may concern:

Be it known that I, CHARLES STUART BAILEY, a subject of the Queen of Great Britain and Ireland, residing at Waltham Abbey, in the county of Essex, Kingdom of Great Britain and Ireland, have invented a new and useful Improved Central-Fire Cartridge, of which the following is a specification.

With a view to provide against escape of gas from what are known as "central-fire gas-tight cartridges" their cores are now usually composed of the following several metal and paper parts, namely: a paper tube, an inner tube-lining, a base-cup, a cap-chamber, a percussion-cap, an anvil, and a paper packing. The blow of the plunger of the gun is given directly onto the crown of the cap to ignite the charge, and the sides of the cap must exactly fit the cap-chamber to prevent escape; also the inner tube-lining must exactly fit and expand with the tube or gas escapes behind it and out over the base-cup. In practice it is found that there is an escape of gas from cartridges so made, and with hammerless guns as recently introduced such gas finds its way into the locks and breech mechanism, and after repeated firing the corrosive deposit from the gases is liable to be detrimental to the working of the gun.

Now, my invention is designed to prevent escape of gases and to produce cartridges specially adapted for hammerless guns. I attain these objects by the combination of parts illustrated in the accompanying drawing, which is an enlarged central longitudinal section of so much of a central-fire cartridge as is necessary to illustrate my invention.

I do away with the usual cylindrical inner tube-lining, and instead thereof I carry up the outer metallic cup, *g*, sufficiently high to give support to the paper tube *a* on the outside. About half an inch is a suitable height. I make this outer metallic cup to inclose the inner metallic cup and also the crown of the percussion-cap, and I construct it of very thin brass—.005 inch is a suitable thickness—to offer as little resistance as possible to the plunger of the

gun, and also that it may better fulfill the requirements of a tube-lining. The end of the cup is indented around the cap *d* to show that the cap is in its proper position. *e* is the anvil.

The inner iron cup, *b*, must be sufficiently strong to withstand the blow of the plunger without concaving or miss-fires will result. I find that sheet-iron .013 inch thick is a suitable thickness. The edges of the cup are thinned off and turned over to fill the bead of the finished cartridge and prevent burst rims. *c* is the cap-chamber, the flange of which is supported by the inner cup, *b*, and the paper pack-ing *f*.

I am aware that prior to my invention central-fire cartridges have been made with an inner and an outer cup inclosing a mass of fulminate between them, and I do not claim such a combination; but

What I do claim is—

1. In a central-fire cartridge, the combination of an inner metallic cup fitting and supporting the bead of an outer metallic cup, and a cap-chamber with flange interposed and held by and between said metallic cups, substantially as described and illustrated.

2. In a central-fire cartridge, the combination of a cap-chamber, an anvil, an inner metallic cup sufficiently strong to withstand the blow of a plunger, striker, or exploding-pin without concaving, a paper packing, and an outer metallic cup, said cap-chamber being constructed with a flange interposed and held by and between said metallic cups, substantially as described and for the purpose specified.

3. In a central-fire cartridge, the combination of a paper tube, a paper packing, a flanged cap-chamber, with anvil and percussion-cap therein, an inner metallic cup acting in the double capacity of a support to the flanged cap-chamber and as a preventive to burst rims, and a thin outer metallic cup such as to oppose little resistance to the plunger, striker, or exploding-pin, the whole arrangement being such that said outer metallic cup incloses both the inner metallic cup and the crown of

the percussion-cap, and also acts as a support to the paper tube, substantially as described, and for the purposes specified.

4. In a central-fire cartridge, the combination, with a paper tube, a cap-chamber with anvil and percussion-cap, a paper packing, and an inner metallic cup, of an outer metallic cup forming a support to said paper tube, inclosing the crown of said percussion-cap and indented around said cap to indicate that same

is in its proper position, substantially as described.

CHARLES STUART BAILEY.
